Jacob Beesley & E. J. Delany, of Philadelphia, Pa.
Assignors to
Cronson, Stuart & Peterson, of the same place
Letter Patent No. 901, Dated June 23, 1857.

The schedule referred to in this Letter Patent, and making part of the same.

To all to whom these Presents shall come:

Be it known that we, Jacob Beesley and Edward J. Delany, of Philadelphia, and State of Pennsylvania, have invented a new design for Parlor Cooking Stove, and that the following is a full, clear and exact description of the principle or character which distinguishes it from all other things before known, and of the usual manner of making, modifying and using the same, reference being had to the accompanying drawings.

Fig: 1. Represents the front of the stove and doors belonging thereto, illustrating the design thereof.

Fig: 2. Represents the top plate of the stove, illustrating the design thereof.

Fig: 3. Represents the back plate of the stove, illustrating the design thereof.

24

Des. 901

Fig. 4. Represents the end plate of the stove, illustrating the design thereof.

These drawings illustrate our design for the Parlor Cooking stove, other parts of the stove being plain and ornamental at pleasure.

What we claim as our invention is the design of parlor

cooking stove as herein above illustrated and set forth.
